US0D1109624S

(12) United States Design Patent (10) Patent No.: US D1,109,624 S
(45) Date of Patent: * Jan. 20, 2026

(54) ORNAMENT

(71) Applicant: Guangzhou Yuanshang Technology Co., Ltd., Guangdong (CN)

(72) Inventor: Jinlu Xu, Shanghang County (CN)

(73) Assignee: Guangzhou Yuanshang Technology Co., Ltd., Guangzhou (CN)

() Term: 15 Years

(21) Appl. No.: 29/942,239

(22) Filed: May 14, 2024

(51) LOC (15) Cl. 08-06

(52) U.S. Cl. D8/305
USPC D8/305

(58) Field of Classification Search

USPC D11/1-6, 11-16, 17, 18, 26-40, 48, 50,
D11/79, 81, 86, 91, 92; D8/300, 305,
D8/312, 317

CPC A44C 25/001; A44C 25/007; E05B 1/00;
E05B 1/0007
